CLAIM

The ornamental design for the jewelry piece having decorative element, as shown and described.

DESCRIPTION

FIG. 1 is a top, front and right side perspective view of jewelry piece having decorative element, showing the new design;

FIG. 2 is a left side view thereof;

FIG. 3 is a right side view thereof;

FIG. 4 is a front plan view thereof;

FIG. 5 is a rear plan view thereof;

FIG. 6 is a top view thereof; and,

FIG. 7 is a bottom view.

The broken lines illustrate portions of the jewelry piece having decorative element and form no part of the claimed design.

1 Claim, 4 Drawing Sheets(56)
